UNITED STATES PATENT OFFICE.

WILLIAM E. D. STOKES, JR., OF NEW YORK, N. Y., AND GEORGE W. DAVIS, OF HOBOKEN,
NEW JERSEY, ASSIGNEES TO WILLIAM E. D. STOKES, OF NEW YORK, N. Y.

RECEIVING DEVICE FOR WIRELESS SYSTEMS.

1,089,091.

Specification of Letters Patent.

Patented Mar. 3, 1914.

Application filed December 9, 1908. Serial No. 463,634.

To all whom it may concern:

Be it known that we, WILLIAM E. D. Stokes, Jr., and GEORGE W. Davis, citizens of the United States, residing at New York, in the county of New York and State of New York, and at Hoboken, county of Hudson, State of New Jersey, respectively, have invented a new and useful Receiving Device for Wireless Systems, of which the following is a specification.

The object of this invention is to provide a new and improved receiving device for wireless telegraph or telephone systems.

In those systems employing what is known as the imperfect contact, frequent adjustments have to be made of the contact which often interrupts the continuity with which the message can be received and leads to difficulty in the service. To overcome this objection, we provide a system by which a large number of contacts are provided, any one of which instantly can be brought into circuit so that if one contact gives out or works imperfectly, another contact can be almost immediately utilized. The contact element which we preferably employ comprises a particular kind of iron pyrites, such as is found in nature in non-crystalline form and which has a more or less carbonaceous shale embedded therein. To utilize these improvements, we preferably arrange one or more elements of this material on a stand and arrange a plurality of contacts with the various faces of each element so that different portions of the same element can be used. We also provide electric switching mechanism so that any one of the contacts can be quickly thrown into circuit. By this arrangement, the contacts may be adjusted to various resistance and degrees of sensitiveness and any desired contact can be quickly thrown into circuit without having to lose time by making adjustment when receiving messages.

One embodiment of the invention is represented in the accompanying drawing, referring to which,

Figure 1 is a diagrammatic view illustrating a wireless system with our invention applied thereto. Fig. 2 is a plan view of the contact arrangement on an enlarged scale, and Fig. 3 is a sectional view on the line 3—3 on a still larger scale.

Referring to the drawing and in detail, A designates an aerial which is connected to the ground or earth E in any of the usual ways. The aerial goes through the primary B of a transformer or induction coil, the secondary C of which is connected to form the receiving circuit. In this receiving circuit we place condenser or capacity D which may be adjustable and an adjustable resistance or resistances F—F. A battery G may also be included in the circuit. A telephone or other receiver H is included in the receiving circuit. The receiving circuit is also preferably provided with a switch I by which said circuit can be cut out when messages are being sent or when the receiving circuit is not to be used. Bridging the receiving circuit in the usual manner is a responding circuit 10—11 in which is placed the imperfect contacts hereinafter described. The circuit arrangements hereinbefore described are of an ordinary type and any other form or arrangement may be used.

The plurality of imperfect contacts is arranged in the bridging circuit 10—11 as follows: On a suitable base of insulating material 12 is arranged a series of posts 13 each having an upwardly projecting stem 14 which is screw-threaded. A piece of the element which is used, which is preferably iron pyrites of a non-crystalline form having embedded therein more or less carbonaceous shale, has a hole bored therethrough and is fitted or placed on the stem 14. This element is represented by P in the drawing and forms the imperfect contact. The same is rigidly held on the stem 14 by a thumb nut 15 threaded on said stem. Each post 13 is connected by a wire 16 to a common wire 17 which is connected in the circuit 10—11. Surrounding each stand 13 is a plurality of stands or uprights 18, four being shown in the drawing as surrounding each stand 13. Threaded into each upright 18 is a screw 19 which has a fine tip 20 which may be made of platinum or any desired material to contact with the element P. Each of said screws 19 has an adjusting milled head 21 and a check nut 22 is also threaded on the same. By this arrangement, the contact of each point 20 with the element P can be accurately and sensitively adjusted and the adjustment can be fixed by check nut 22.

Each of the stands or uprights 18 is connected by a wire 23 to a button or post 24, which buttons or posts 24 are arranged in line near one side of the base 12, as illustrated in Fig. 2.

Brackets 25 are secured to the piece 12 and between said brackets is arranged a metallic rod 26. Sliding on this rod 26 is a block 27 which carries a spring arm 28 which can contact with any one of the posts or buttons 24. A screw 29 is threaded into the block 27 so that the block can be locked in any position on the rod 26.

One of the brackets 25 is provided with a binding post 30 to which the circuit 10-11 is connected. By this arrangement, any one of the contacts can be brought into the circuit 10-11 by sliding the block 27 along the rod 26 so that the spring arm 28 will contact with the proper button 24. The contacts are adjusted at leisure to obtain the desired resistance and sensitiveness. Then when receiving, if it is found that any particular contact is not working accurately or as sensitively as desired, by sliding the block 27 along the rod 26, any one of the contacts can be tried and the one which is the most responsive can be left in the circuit. This can be done very quickly by the operator, as it requires no adjustment.

We have found that it is a peculiarity of mineral contacts that the same have some spots thereon which are more sensitive than others and that there are usually a plurality of such surfaces around a piece of mineral. By arranging a plurality of contacts around a single element, advantage can be taken of

this fact to get a number of contacts from one element.

We have found in practice that the iron pyrites of the character described makes a very sensitive and nice working receiving or responding element.

The details and arrangements herein shown and described may be greatly varied by a skilled electrician without departing from the scope of our invention as expressed in the claims.

Therefore, having thus fully described our invention, what we claim and desire to secure by Letters-Patent is:—

1. A receiver for wireless systems having an element composed of iron pyrites having carbonaceous shale embedded therein.

2. A receiving arrangement for wireless systems, comprising a base, a plurality of responsive elements carried thereby, stands or uprights thereon supporting a plurality of adjustable contacts engaging each element, a system of buttons or posts on said base connected with said contacts; a rod carried by said base, and a sliding block on said rod which can be moved to engage any one of said buttons or posts, whereby any contact can be thrown into circuit. 65

In testimony whereof we have hereunto set our hands, in the presence of two subscribing witnesses.

WILLIAM E. D. STOKES, JR.
GEORGE W. DAVIS.
